SHOE LACE

Filed Jan. 24, 1927

INVENTOR.
C. H. GUNN
BY *Benj. L. Webster*
ATTORNEY.

UNITED STATES PATENT OFFICE.

CHARLES H. GUNN, OF SAN FRANCISCO, CALIFORNIA.

SHOE LACE.

Application filed January 24, 1927. Serial No. 163,228.

This invention relates to improvements in shoe laces, the object of the invention being to produce an elastic lace which will when inserted in the shoe allow the instep of the shoe to conform to the instep of the wearer automatically, and thus prevent binding and cramping of the instep in the shoe. Where cotton or leather shoe strings are used the binding effect thereof over the instep very often causes considerable pain and many times causes the instep to be seriously calloused and otherwise injured. By the use of my self-conforming shoe lace, however, this callousing will not be encountered and the shoe will fit the wearer in an easy and comfortable way without any binding.

A further object of the invention is to produce a simple and inexpensive device and yet one which will be exceedingly effective for the purpose for which it is designed.

The objects I accomplish by means of such structure and relative arrangement of parts as will fully appear by a perusal of the following specification and claim.

In the drawings similar characters of reference indicate corresponding parts in the several views:

Fig. 1 is a view of the complete shoe string partly broken out at one point in order to show the preferred internal construction.

Fig. 2 is a sectional view taken on the line 2—2 of Fig. 1.

Referring now more particularly to the characters of reference on the drawings, the numeral 1 denotes generally the shoe lace having the usual tips 2. The lace 1 is made up preferably of an outer extensible casing 3 of cotton or like woven fabric. Within

this outer casing are disposed two or more elastic rubber elements 4 preferably square in cross section and each being individually covered with an extensible casing 5 also made up of cotton or like woven fabric.

The lace constructed in the manner described provides a very strong and durable lace, and yet one having the advantages and utility set forth in the preamble of this specification, since the action of the elastic lace when inserted in the eyelets of the shoe will be such as to cause the upper of the shoe across the instep to be self-conforming to the foot of the wearer, as will be obvious.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A shoe lace comprising a plurality of longitudinal elastic elements independent of each other, extensible casings about the elements, said casings being independent of each other, and a common extensible casing surrounding and enclosing said first named casings and the elements therein, and being independent thereof.

In testimony whereof I affix my signature.

CHARLES H. GUNN.
